E. W. NEDVED

CALF WEAVER

Filed March 5, 1920

Inventor
E. W. Nedved.

By *John Murphy Jr.*
Attorney

UNITED STATES PATENT OFFICE.

EMANUEL WILLIAM NEDVED, OF MILLBORO, SOUTH DAKOTA.

CALF WEANER.

Application filed March 5, 1920. Serial No. 363,426.

To all whom it may concern:

Be it known that I, EMANUEL WILLIAM NEDVED, a citizen of the United States, residing at Millboro, in the county of Tripp 5 and State of South Dakota, have invented certain new and useful Improvements in Calf Weaners; and I do hereby declare the following to be a full, clear, and exact description of the invention, such as will enable others skilled in the art to which it 10 pertains to make and use the same.

The object of this invention is to provide a simple inexpensive and efficient calf weaner, applicable without inconvenience to the 15 animal and of such a construction as to permit of eating or grazing without interference and yet designed to effectually serve its purpose and to come into operative position when the calf raises the head, and with these 20 objects in view the invention consists of a construction and combination of parts of which a preferred embodiment is shown in the drawing wherein:

Figure 1 is a side view of the device in 25 the applied position.

Figure 2 is a plan view of the same.

The apparatus consists essentially of a shield or nose piece 10 of generally cross sectionally semi-cylindrical form having the 30 rearwardly extending ears 11 disposed in a substantially upright position at opposite sides of a curved space 12 for the exposure of the upper portion of the head or face and the eyes of the wearer, the shield being 35 tapered toward its front end and provided at the extremity with radially projecting spurs 13 which in the construction illustrated are carried by a fastening plate 14 which is 40 attached by rivets 15 or the equivalent thereof to the material of the shield, preferably of sheet metal or the equivalent thereof.

The means for attaching the device to the head of the animal consists of the throat latch 17 which is preferably adjustable as by means of a buckle 18, a nose strap 19 and 45 a head strap 20, the latter also being adjustable by means of a buckle 21, said throat latch and nose strap being preferably formed of a single piece and the throat latch, nose piece and head strap being pivotally connected to the rearwardly extending ears of the shield at the point 22 by means, in the construction illustrated, of rivets to the end that the shield may be pivotally moved with reference to the fastening straps forming the 50 halter to permit of the free movement of the head of the animal when depressed for the purpose of feeding, drinking or grazing, but adapted to drop down upon the nose when the head is raised, to prevent effective 55 approach to the cow.

What is claimed is:

A calf weaner comprising an elongated longitudinally tapering transversely curved sheet metal shield, a portion of the rearward edge of said shield being cut away to expose the upper part of the face of the wearer, relatively wide rearwardly extending side plates formed by said cut away portions, a longitudinally curved angle member 65 secured to the forward end of said shield, upstanding spurs carried by said member, attaching means pivotally connected to the side plates adjacent their rear ends, and said side plates serving to prevent lateral displacement of the shield.

In testimony whereof I affix my signature in presence of two witnesses.

EMANUEL WILLIAM NEDVED.
